DESIGN FOR AN UPHOLSTERED DAVEN- PORT

William L. Swearingen, Portland, Oreg.

Application March 17, 1937, Serial No. 68,211

Term of patent 3½ years

To all whom it may concern:

Be it known that I, William L. Swearingen, a citizen of the United States and a resident of Portland, in the county of Multnomah, State of Oregon, have invented a new, original, and ornamental Design for an Upholstered Davenport, of which the following is a specification, reference being had to the accompanying drawing, forming a part thereof.

I claim:

The ornamental design for an upholstered davenport as shown.

WILLIAM L. SWEARINGEN.
